UNITED STATES PATENT OFFICE.

EDWIN B. SMITH, OF MARION, INDIANA, ASSIGNOR TO THE MARION MACHINE FOUNDRY AND SUPPLY COMPANY, OF MARION, INDIANA, A CORPORATION.

GRATE FRAME.

1,418,483.

Specification of Letters Patent. Patented June 6, 1922.

Application filed September 7, 1920. Serial No. 408,570.

To all whom it may concern:

Be it known that I, EDWIN B. SMITH, a citizen of the United States, residing at Marion, in the county of Grant and State 5 of Indiana, have invented a new and useful Grate Frame, of which the following is a specification.

This invention relates to means for locking together the side frames and end grate bars 10 of furnaces utilizing rocking grates.

Various means have been devised heretofore for connecting the end grate bars to the side frames but they have been open to many objections, from a practical stand- 15 point, many of them causing distortion of the structure when in use, others being difficult to install under some conditions, and others becoming dislocated after a short period of use.

20 It is an object of the present invention to provide an improved means for locking the end grates to the side frames whereby the erector is enabled, after placing the frame in position in the furnace, to drop the end 25 bars down into their proper positions where they will be properly engaged and securely held and locked.

With the foregoing and other objects in view, which will appear as the description 30 proceeds, the invention consists of certain novel details of construction and combinations of parts which will be hereinafter more fully described and pointed out in the claim, it being understood that various changes 35 may be made in the construction and arrangement of the parts without departing from the spirit or sacrificing any of the advantages of the invention.

In the accompanying drawings the preferred form of the invention has been 40 shown.

In said drawings—

Figure 1 is a view partly in side elevation and partly in section showing the grate bar 45 in engagement with the side frames.

Figure 2 is a perspective view of one of the end bars of the grate.

Figure 3 is a perspective view showing the inner side of one end portion of one of 50 the side frames and the locking lugs thereon.

Figure 4 is a similar view showing the

outer side of one end portion of a side frame.

Referring to the figures by characters of reference, 1 designates the end bar of a 55 grate, the same being provided at each end with a depending lug 2. The bar has a longitudinal series of apertures 3 in the top thereof and is provided with the usual laterally extending teeth 4, adapted to cooperate 60 with the teeth of the adjoining rocking bars, not shown, of the grate. For the purpose of supporting and locking the end bar 1 in position, the side frames, indicated at 5 which are mounted in the usual manner, are 65 formed with inwardly extending lugs 6 having openings therein for the reception of the lugs 2 on the bar 1. Hooks 7 are also formed on the inner sides of the side frames and are adapted to extend upwardly into the 70 end openings 3 in the bar 1. Thus it will be seen that after the side frames 5 have been lowered into position in the furnace, the end bars 1 can be lowered to seat the lugs 2 in the lugs 6 and the hooks 7 in the open- 75 ings 3 and the parts will be held securely together without danger of becoming accidentally displaced and without causing distortion of the furnace when in use.

What is claimed is:—

In a grate the combination of side members and a bar inserted therebetween, each side member being provided with an inwardly extending hook upon the upper portion thereof and with an inwardly extending apertured lug upon the lower portion thereof, said bar being provided with a longitudinal series of apertures opening downwardly through the upper portion thereof, with downwardly extending lugs at the ends 90 of the bar and with laterally extending teeth, the end apertures in the bar constituting seats for the hooks, and the apertured lugs constituting seats for the downwardly extending lugs.

In testimony that I claim the foregoing as my own, I have hereto affixed my signature in the presence of two witnesses.

EDWIN B. SMITH.
